UNITED STATES PATENT OFFICE.

ROBERT LEE PAGE, OF GREENVILLE, MISSISSIPPI.

TYPE-WRITER ATTACHMENT.

1,321,664.

Specification of Letters Patent. Patented Nov. 11, 1919.

Application filed May 10, 1919. Serial No. 296,222.

To all whom it may concern:

Be it known that I, ROBERT LEE PAGE, a citizen of the United States, and a resident of Greenville, in the county of Washington and State of Mississippi, have invented new and useful Improvements in Type-Writer Attachments, of which the following is the description.

This invention relates to paper feeding attachments particularly adapted to be used in connection with typewriters although not restricted to this particular use.

An important object of the invention is to provide in an attachment of the above mentioned character a means whereby the paper may be automatically fed to the platen of the typewriter.

A further object of the invention is to provide in an attachment of the above mentioned character a means whereby the sheets of paper may be retained in a stacked relation within the device.

A further object of the invention is to provide in an attachment of the above mentioned character a means whereby certain elements thereof may be adjusted to accommodate various sizes of sheets of paper without altering or affecting the operation of the device.

A further object is to provide a device of the above mentioned character which may be easily installed upon a typewriter without altering or changing any part of the construction.

A further object is to provide a device of the above mentioned character which is simple in construction, cheap to manufacture, strong, durable and reliable in operation.

Other objects and advantages of the invention will be apparent during the course of the following description taken in connection with the accompanying drawings.

In the drawings, forming a part of this specification and in which like numerals are employed to designate like parts throughout the same,

Figure 1 is a longitudinal sectional view of the device embodying my invention, the device being shown as applied to a typewriter.

Fig. 2 is a sectional view taken on line 2-2 of Fig. 1.

Fig. 3 is a top plan view of the device, 55 and,

Fig. 4 is a sectional view taken on line 4-4 of Fig. 1.

In the drawings, wherein for the purpose of illustration, is shown a preferred form of my invention, the numeral 5 indicates as a whole a typewriter having a transversely disposed shaft 6 upon which is mounted the conventional type of platen 7 adapted to be actuated by means of hand grips 8. The platen 7 together with the several elements 65 comprising the supporting frame therefor is adapted to move transversely across the typewriter and is supported in part by guide rod 9. The transversely movable supporting frame which is indicated as a whole by 70 the numeral 10 carries a paper guide 11 arranged in proximity to and partially encircling the platen 7 and is further provided with a second paper guide 12 which moves bodily with the platen 7 and the supporting 75 frame 10. The various elements of the typewriter so far described and shown are common to those of the Remington type but the device embodying my invention by slight modifications may be used in connection with 80 any form of typewriters wherein a platen supported by a transversely movable frame or carriage is employed.

The device embodying my invention comprises a rectangular receptacle 13 having 85 side members 14 and a closed end as shown at 15. As a means for retaining sheets of paper as shown at 16 in a stacked relation I employ what might be termed a paper gage which comprises a back stop 17 having 90 ears 18 bent to engage the sides 14 of the receptacle as clearly shown in Fig. 3. The back stop 17 is adapted to be moved longitudinally within the receptacle 13 so that the ends of the sheets 16 regardless of their 95 lengths may be brought into contact therewith. As a means for retaining the sheets 16 in a central position within the receptacle 13 there is provided a pair of wings 19 one end of each wing being bent as shown at 20 100 to engage the back stop 17. The wings 19 are adjustable transversely with respect to the receptacle 13 so that the longitudinal edge of the sheets 16 may be brought into contact therewith. It is seen therefore that 105 by the construction embodied in elements 17, 18, 19 and 20 a given stack of paper may be retained in a desired position within the receptacle. To the back stop 17 there is connected a flange 21 to which is slidably con- 110

nected a sheet retainer 22, the sheet retainer being connected to the flange 21 by means of a screw 23 passed through an elongated slot 24 within the retainer 22.

5 To the sides 14 of the receptacle there is connected a pair of arcuate shaped ears 25 each of which is provided with an arcuate shaped slot 26, the arcuate shaped slots being concentric with the center of the platen 7. 10 Within the slots 26 there is journaled a rotatable shaft 27 which is prevented from moving transversely with respect to the container by collars 28 secured to the shaft and disposed on opposite sides of the ears as 15 clearly shown in Fig. 2. To the shaft 27 intermediate its ends there is secured a pair of disks 29 having rubber faces as shown at 30, the rubber faces being adapted to engage always the uppermost sheet of a pile 20 of sheets as clearly shown in Fig. 1. To the ends of the shaft 7 there is connected a pair of sprockets 31 which are in turn connected to sprockets 32 secured to the shaft 6, the sprockets 31 and 32 being connected 25 by means of sprocket chains 33.

The sides 14 of the receptacle at their forward ends are provided with upstanding supports 34 which are connected at their upper ends by means of a deflector 35 bent to 30 provide an apron 36 which terminates in proximity to the paper guide 11 and platen 7, it serving in conjunction with the paper guides 11 and 12 as a means for directing the sheets of paper into engagement with 35 the platen so that the paper may be fed into the typewriter by revolving the platen.

The device as a whole is secured to the paper guide 12 by means of set screws carried by ears 38 adapted to receive the paper guide 12, the paper guide 12 being engaged at its longitudinal edges by the set screws 37. In use the sheets of paper 16 are placed in the receptacle 13 under the rubber faced disks 29, the rubber faces of the disks being held in engagement with the uppermost sheet by the weight of the shaft 27 together with the sprockets 31 and disks 39 secured thereto. As hereinbefore described the elements 17 and 19 may be adjusted to accommodate various sizes of paper in order to retain the paper centrally within the receptacle 13. By rotating the platen 7 rotation

is imparted to the shaft 27 causing the rubber faced disk to rotate in the direction of the arrow of Fig. 1 whereupon the uppermost sheet is moved from under the retainer 22 and deflected by means of the apron 36 and the guides 11 and 12 into contact with the platen thereby placing the sheet into position to be further moved into typewriting position by rotating the platen 7 as is apparent. 55

60 It is understood that the form of my invention herewith shown and described is to be taken as a preferred example of the same, and that various changes in the shape, size and arrangement of parts may be resorted to without departing from the spirit of the invention or the scope of the subjoined claim. 65

Having thus described my invention, what 70 I claim as new and desire to secure and protect by Letters Patent of the United States, is:

A typewriter attachment of the character described comprising a receptacle adapted to be connected to the typewriter, said receptacle being adapted to receive a plurality of sheets of paper to be fed to the typewriter platen, a pair of ears secured to the sides of said receptacle, said ears being provided 75 with arcuate shaped slots, a rotatable and vertically movable shaft mounted within said slots, said shaft being provided with a plurality of disks adapted to engage the uppermost sheet of paper within said receptacle, operable means connecting said shaft with the platen for rotating said shaft whereby the paper may be fed from said receptacle to the platen, an adjustable back-stop arranged within said receptacle, said 80 back-stop having its ends slidably engaging the sides of said receptacle to permit longitudinal adjustment of said back-stop with respect to said receptacle, a pair of wings extending longitudinally with respect to said 85 receptacle, said wings being adjustably attached to said back-stop to permit transverse adjustment thereof with respect to said receptacle, and a vertically movable paper retainer mounted within said receptacle, said 90 retainer being secured to said back-stop intermediate the ends thereof. 95 100

ROBERT LEE PAGE.
